UNITED STATES PATENT OFFICE.

CHARLES M. WHITMAN, OF MEEKER, OKLAHOMA.

CLOTHES-POUNDER.

1,109,494.

Specification of Letters Patent.

Patented Sept. 1, 1914.

Application filed August 15, 1913. Serial No. 784,931.

To all whom it may concern:

Be it known that I, CHARLES M. WHITMAN, a citizen of the United States, residing at Meeker, in the county of Lincoln and State of Oklahoma, have invented new and useful Improvements in Clothes-Pounders, of which the following is a specification.

This invention relates to clothes pounders and it consists in the novel features herein-
10 after described and claimed.

An object of the invention is to provide a pounder of simple structure which is adapted to operate effectually upon the clothes to speedily remove dirt from the
15 same as the pounder is reciprocated upon the clothes.

With the above objects in view the pounder comprises a funnel shaped body having a ferrule end adapted to be applied to a
20 staff or handle. The body is provided at a point between its ends with an annular shoulder against which is located a partition. The partition is located within the sides of the body. A flange is attached to
25 the partition and is provided at its upper portion with openings. The flange is approximately frusto-conical in configuration and its end of smaller diameter is downwardly disposed. A pipe is transversely disposed through the body and the flange
30 immediately below the partition and is provided at its upper side with an opening which traverses its length and is provided at its lower side with an opening which is approximately centrally positioned with relation to the said flange.

In the accompanying drawing:—Figure 1 is a vertical sectional view of the pounder. Fig. 2 is a bottom view of the same.

40 The pounder comprises a funnel shaped body 1 having at its smaller end a ferrule 2 in which the end of a handle or staff may be inserted and secured in any suitable manner. The body 1 is provided at a line be-
45 tween its ends with an annular shoulder 3. A partition 4 is located in the body 1 and is secured to the same at the shoulder 3 by means of solder or other suitable securing material. A flange 5 is secured to the lower
50 side of the partition 4 and is provided at its upper edge with openings 6. The lower edge of the flange 5 terminates in a plane above the lower edge of the body 1. The flange 5 is approximately frusto-conical and

its end of smaller diameter is lowermost. A 55 pipe 7 passes transversely through the flange 5 and the opposite sides of the body 1 below the partition 4 and the said pipe is provided at its upper side with an opening 8 which traverses the length of the pipe. 60 The pipe 7 is provided at its lower side with an opening 9 which is approximately concentrically positioned with relation to the flange 5.

In the operation of the pounder it is apparent when the same is forced in a downward direction upon the clothes the lower edge of the body 1 when it encounters the clothes will have a tendency to spread the same. Upon further downward movement 70 of the body 1 the clothes will be distended up into the lower portion of the body so that the clothes come in contact with the lower edge of the flange 5 and the said flange prevents the clothes from coming in 75 contact with the pipe 7 and closing the openings thereof. Therefore during the downward movement of the body 1 the clothes are stretched and the air in the lower portion of the body 1 may escape from the 80 same through the pipe 7, thus as the clothes are pushed in downward direction the water will pass up through the clothes and remove the dirt from the same.

When the pounder is moved in an up- 85 ward direction the clothes will have a tendency to follow the same until the ends of the pipe 7 are moved above the surface of the water in which the clothes are immersed. As soon as this takes place the external 90 air enters the pipe 7 and passes through the openings 8 and 9 in the same into the lower portion of the body 1 and thus a vacuum under the partition 4 is destroyed and the clothes will fall from the lower end of the 95 pounder.

Therefore it will be seen that a clothes pounder of simple structure is provided and that the same will operate effectually to remove the dirt from the clothes.

Having thus described the invention what is claimed is:—

A pounder comprising a conical body, a partition located in the lower portion of the body, an annular flange attached to the partition and provided at its upper edge portion with openings, a pipe passing transversely through the flange and the opposite

side portions of the body and spaced from the partition and being provided at its upper side with an opening which traverses its length and provided at its lower side with an opening which is approximately centrally positioned with relation to the flange.

In testimony whereof I affix my signature in presence of two witnesses.

CHARLES M. WHITMAN.
